CECIL E. BRIGHAM INVENTOR.

BY *John B. Brady*

ATTORNEY.

UNITED STATES PATENT OFFICE.

CECIL E. BRIGHAM, OF EAST ORANGE, NEW JERSEY, ASSIGNOR TO C. BRANDES, INC., OF NEW YORK, N. Y., A CORPORATION OF NEW YORK.

LOUD SPEAKER.

Application filed June 14, 1924. Serial No. 720,087.

To all whom it may concern:

Be it known that I, CECIL E. BRIGHAM, a citizen of the United States, residing at East Orange, in the county of Essex and State of New Jersey, have invented certain new and useful Improvements in a Loud Speaker, of which the following is a specification.

My invention relates broadly to electromagnetic sound reproducers and more particularly to a loud speaker designed particularly for the efficient reproduction of frequencies within the range employed in radio broadcast reception.

One of the objects of my invention is to provide a loud speaker construction wherein the mechanical inertia of the moving parts of the reproducer is substantially eliminated.

Another object of my invention is to provide a loud speaker construction employing a true floating armature eliminating mechanical friction offered by fulcrum points and pivoted mountings usually employed to support the armature.

Still another object of my invention is to provide an arrangement of permanent magnet structure and an electromagnetic structure having a hollow core with opposite pole at opposite ends thereof with a freely floating armature mounted within the hollow core and connected with a diaphragm converting electrical energy into sound vibrations.

A further object of my invention is to provide an assembly of permanent magnet structure and an electromagnetic structure adjacent a casing enclosing a sound reproducing diaphragm. The permanent magnet structure having pole pieces projecting toward each other with flat overlapping faces. The electromagnet structure being disposed between the inwardly projecting pole pieces and having a hollow core with a freely floating armature within the hollow core and between the overlapping pole pieces, the armature being connected with the sound reproducing diaphragm.

My invention will be more clearly understood by reference to the accompanying drawings, in which:

Figure 1, is a cross sectional view through the loud speaker construction of my invention; Fig. 2 is a plan view looking beneath the loud speaker construction illustrated in

Fig. 1; and Fig. 3 is a side view of the electromagnetic sound reproducer looking toward the end of the freely floating armature and showing the overlapping pole pieces of the permanent magnet.

Heretofore in the art it has been customary to utilize a telephone receiver unit with various modifications in loud speaker assembly. A telephone unit is quite satisfactory for the electrical reproduction of sound where the received energy does not exceed a particular amplitude. However, where the amplitude of the received energy is very large and the volume of the reproduced sound very considerable, the efficiency of the telephone receiver unit becomes very low. Under these circumstances the reproduced sound is not clear and there is a continuous tendency for the diaphragm to rattle and reproduce extraneous noises. In other types of reproducers it has been proposed to interpose an armature between the sound reproducing diaphragm and the operating mechanism. The armature has normally been mounted between pivots or fulcrum in a given position or otherwise secured or connected to the frame of the reproducer mechanism. These connections have inherently introduced mechanical inertia and friction. In the reproduction of radio broadcast music or speech it is essential that the reproducing mechanism follow the energy variation with rapidity and extreme accuracy. Mechanical inertia and friction often introduce such mechanical resistance that a positive force must be overcome by the minute incoming signaling energy before this relatively weak energy may actuate the sound reproducing diaphragm proper. By my invention I eliminate this undesirable mechanical inertia and friction by providing a true, freely floating armature connected with the sound reproducing diaphragm. I provide a permanent magnet having inwardly projecting pole pieces, each having flat faces directed toward each other in overlapping relationship. An electromagnet is provided between the inwardly projecting pole pieces, the electromagnet having a hollow core so related to the pole faces as to permit an armature to be freely floating within the hollow core and between the overlapping pole faces. The armature is connected with the sound reproducer diaphragm and the incoming signal energy ap-

105

plies itself entirely to actuating the diaphragm proper. In this manner the mechanical efficiency of the reproducing mechanism is largely increased by reducing inherent mechanical losses.

The form of the electromagnetic reproducer illustrated in the drawings and hereinafter described in detail has been found to be one of the practical embodiments of the invention and capable of efficient operation and practical in manufacture and production.

Referring now more particularly to the drawings, the electromagnetic reproducer is shown as comprising a circular casing 1 and 2, the upper and lower sections of which are secured together by means of bolts 3. The upper section 2 of the casing is screw threaded at 4 to receive a ferrule or other form of adapter in which an acoustic horn is mounted. The sound reproducing diaphragm 5 is mounted within the casing formed by sections 1 and 2. It will be understood that these sections might be screw threaded, one into the other with the diaphragm 5 seated between the sections 1 and 2 and that means other than the screws 3 as illustrated may be employed in securing the parts together. The permanent magnet means employed in the reproducer consists of a horseshoe magnet 6 having poles 9 and 10 of opposite polarity. The magnet is suspended from the section 1 of the casing by means of bolts 7 and nuts 8 which pass through pole pieces 30 and 31. The pole pieces 30 and 31 are thereby secured rigidly between the horseshoe magnet 6 and the lower surface 29 of the casing section 1. The pole pieces 30 and 31 project inwardly toward each other as shown in Figure 2. Pole members 14 and 15 are secured on opposite sides of pole piece 30. The pole piece 31 is provided with pole members 16 and 17 secured on opposite sides thereof in a manner similar to the method of securing pole members 14 and 15 on opposite sides of pole piece 30. Each of the pole members, 14, 15, 16, and 17 has a corner cut out at the end thereof, the remaining portion of each pole member forming a flat pole face adjacent each other and arranged in parallel spaced relationship. That is to say pole member 14 is provided with a flat pole face 20, while pole member 15 has a flat pole face 18. The pole member 17 has a flat pole face 19, while pole member 16 has a flat pole face 21. The pole members are so arranged that the pair of pole faces of similar polarity are diagonally positioned with respect to the pole faces of the pair of pole members of opposite polarity. This will be understood when the end 9 of permanent magnet 6 is considered as north while the opposite end 10 of the permanent 6 is considered to be south. Pole faces 21 and 19 in Fig. 1 will then be south

poles while pole faces 18 and 20 in Fig. 1 will be north poles.

An electromagnet winding 24 is provided disposed between the extremities of pole pieces 30 and 31 and between the pole members 14, 15, 16, and 17. The magnet winding 24 is wound upon a hollow core, the opening of which is aligned with the parallel gap between the pole faces of the pole members. Within this hollow core and between the pole faces I mount a true floating armature member 23. The armature 23 may be connected to the sound reproducing diaphragm 5 in a variety of different ways. I have shown the armature 23 connected by means of downwardly depending links 25 and 26 passing through an aperture 22 in the lower portion of section 1 of the casing, and rigidly connected to the diaphragm at spaced intervals as represented at 27 and 28. I may also mount the armature 23 with respect to the diaphragm 5 by means of a depending U shaped strip connected to the center of the diaphragm 5 and straddling the electromagnet winding 24 and the pole members being secured to opposite ends of the armature 23.

It will be seen that the armature in my reproducer is a true freely floating device. There are no frictional contacts or pivots to introduce undesirable friction or mechanical inertia. The signaling energy lead into the electromagnet winding 24 is utilized in the fullest degree to produce a push-pull effect on the armature. No fulcrum points are employed in mounting the armature but a positive air-gap left around the armature so that it is free to vibrate in accordance with the incoming signaling energy.

The armature vibrates with substantially straight line movement in a direction substantially at right angles to the axis of the electromagnet in such manner that the entire amplitude of vibration thus developed may be impressed directly upon the diaphragm. The effect of the electromagnet mechanism is to operate the diaphragm by push-pull forces in a vertical direction with respect to the electromagnet.

While I have illustrated my invention in a certain preferred embodiment I desire that it be understood that modifications may be made and that no limitations are intended upon the invention other than those imposed by the scope of the appended claims.

What I claim and desire to secure by Letters Patent of the United States is as follows:

1. An electromagnetic sound reproducer comprising in combination a casing, a permanent horseshoe magnet, a pole piece secured to the extremity of each side of said horseshoe magnet, a pair of pole members attached to each of said pole pieces, each having extensions directed toward each

- other in overlapped relationship with their faces spaced apart, an electromagnetic winding have a hollow core, a diaphragm carried in said casing, an armature arranged to freely float within said hollow core and extending between said pole pieces and connections between extremities of said armature and said diaphragm for imparting movement to said diaphragm.
- 10 2. An electromagnetic sound reproducer comprising in combination a casing, permanent magnetic means, electromagnetic means located between said permanent magnetic means, a freely floating armature positioned within both of said means, a diaphragm in said casing and a connection between opposite ends of said freely floating armature and said diaphragm whereby vibrations transverse to the axis of said electromagnetic means may be imparted to said diaphragm.
- 15 3. An electromagnetic sound reproducer, comprising in combination a casing, a permanent magnet, a plurality of pairs of pole pieces secured to said magnet each pair of said pole pieces having flat faces projecting toward each other in overlapping relationship, an open cored electromagnet positioned between said pole pieces, a diaphragm carried by said casing and a freely floating armature interposed within said electromagnet and between said pole pieces and connected at its opposite ends with said diaphragm whereby substantially straight line motion transverse to the axis of said electromagnet is imparted to said armature for actuating said diaphragm.
- 20 4. An electromagnetic sound reproducer comprising in combination a casing, a permanent horseshoe magnet, a pole piece secured to the extremity of each side of said horseshoe magnet, a pair of pole members attached to each of said pole pieces, each of said pole members having a corner cut out of the end thereof with the remaining portion of the pole members forming pole faces adjacent each other, an electromagnetic mechanism having a hollow core, a diaphragm carried in said casing and an armature freely floating within said hollow core and between said pole faces and connected at its opposite extremities with said diaphragm, whereby substantially straight line vibration perpendicular to the axis of said electromagnetic mechanism is imparted to said armature for driving said diaphragm.
- 25 5. An electromagnetic sound reproducer comprising in combination a casing, a permanent horseshoe magnet, a pole piece secured to the extremity of each side of said horseshoe magnet, a pair of pole members attached to each of said pole pieces, each pair of said pole members having pole faces offset one with respect to the other, with the offset portion of one pole member on one of said pole pieces diagonally positioned with respect to the corresponding offset portion of an opposite pole member on the other of said pole pieces, said offset portions providing substantially parallel faces, an electromagnet having a hollow core disposed between said pole pieces, a sound reproducing diaphragm and a true floating armature positioned within said hollow core and between said parallel faces and connected at its opposite ends with said diaphragm whereby substantially straight line vibration is imparted to said armature in a direction substantially transverse to the axis of said electromagnet for driving said diaphragm.
- 30 6. An electromagnetic sound reproducer comprising in combination a casing, permanent magnetic means, pole pieces secured to said means and directed toward each other with an air gap separating the extremities thereof, a freely floating armature positioned within said air gap, means for creating a variable magnetic field transverse to the axis of said armature, a diaphragm carried in said casing and a connection between opposite ends of said freely floating armature and said diaphragm whereby vibrations transverse to the axis of said armature may be imparted to said diaphragm in accordance with the variations of said magnetic field.

CECIL E. BRIGHAM.
